DESIGN FOR A THIMBLE

Joy J. Bradley, Sherman Oaks, Calif.

Application November 29, 1944, Serial No. 116,619

Term of patent 7 years

(Cl. D3—19)

To all whom it may concern:

Be it known that I, Joy J. Bradley, a citizen of the United States, residing at 14846 Sutton Street, in the city of Sherman Oaks, in the county of Los Angeles and State of California, have invented a new, original, and ornamental Design for a Thimble, of which the following is a specification, reference being had to the accompanying drawing, forming a part thereof, in which;

Figs. 1 and 2 are side views of opposite sides of a thimble showing my new design.

Fig. 3 is a bottom view, and

Fig. 4 is a cross sectional view thereof.

I claim:

The ornamental design for a thimble, as shown.

JOY J. BRADLEY.
